DISPENSER STOPPER FOR A BOTTLE

August L. Voight, Berea, Ohio

Application December 30, 1952, Serial No. 22,916

Term of patent 14 years

(Cl. D58—10)

To all whom it may concern:

Be it known that I, August L. Voight, a citizen of the United States, residing at Berea, county of Cuyahoga, and State of Ohio, have invented a new, original, and ornamental Design for a Dispenser Stopper for a Bottle, of which the following is a specification, reference being had to the accompanying drawing, forming a part thereof, in which:

Fig. 1 is a front elevational view of a dispenser stopper for a bottle, showing my new design;

Fig. 2 is a side elevational view, looking from the right hand side of Fig. 1;

Fig. 3 is a side elevational view, looking from the left hand side of Fig. 1;

Fig. 4 is a top plan view, and
Fig. 5 is a bottom plan view thereof.

I claim:

The ornamental design for a dispenser stopper for a bottle, as shown.

AUGUST L. VOIGHT.
